A. Robbins,

Railroad Frog,

No 56,271,

Patented July 10, 1866.

UNITED STATES PATENT OFFICE.

ADDISON ROBBINS, OF ORANGE, MASSACHUSETTS.

IMPROVED RAILWAY-FROG.

Specification forming part of Letters Patent No. 56,271, dated July 10, 1866.

To all whom it may concern:

Be it known that I, ADDISON ROBBINS, of Orange, in the county of Franklin and State of Massachusetts, have invented a new and useful Improvement having reference to Railways; and I do hereby declare the same to be fully described in the following specification and represented in the accompanying drawing, which is a top view of a railway-track and a branch track provided with my invention.

The said invention relates to the junction of two crossing rails or the angle-piece at such junction. Instead of making the said angle-piece stationary in the ordinary way, I construct it and portions of the two rails next its vertex movable, in manner as hereinafter described.

When the angle-piece is stationary it is apt to soon become worn or broken down at its vertex in consequence of the concussions it is subjected to from the wheels in passing upon it. The ends of the two rails next adjacent to its vertex are also liable to be worn down more or less by concussions of the wheels while they may be in the act of either entering upon or passing off them.

My invention is designed to dispense with the usual flange-passages between the rails and the angle-piece, and by so doing to form what may be termed, for all practical purposes, a "continuous bearing-surface" for the wheel to run on while passing from the rail to the angle-piece, or from the latter to the former.

In the drawings, A A' and B B' denote the crossing-rails of the main track and turn-out. G is the angle-piece at the junction of these rails. This angle-piece, instead of being stationary, as it generally is, turns on a center or pivot, f, situated at or near its base. It is also jointed by a pivot, c, to a movable carriage or slider, E, which extends underneath it transversely, and is supported on a rail or plate, F. The slide E may be furnished with friction-wheels, by which it may be supported on the plate F.

Two short rails, C D, in continuation of the rails A B, or arranged with respect to them and the angle-piece G in manner as represented, are to be supported so as to be able to

turn on centers or pins e e, and are connected with the slide or carriage E by means of arms a b, arranged on opposite sides of the angle-piece G, and jointed to the said slide-bar or carriage E at d d. The two auxiliary rails C D, where they are next to the angle-piece, are supported on and secured to a stop carriage or slider, K, designed to move on a bed-plate, L, and between two stops, M N. The two rails C D may also have one or more other movable supporting-slides, I, each to rest and slide on a bed-plate, H.

By moving the angle-piece G so as to bring its smaller end or vertex into conjunction with the rail C we shall move the slide K up to the stop M. So, by moving the angle-piece into conjunction with the rail D, we shall move the slide K against the stop N. These stops, with the slide K, thus serve to arrest the movements of the angle-piece G and the two rails C D at the periods of conjunction of the angle-piece with such rails.

When the angle-piece is in conjunction with the rail C the two make, with the rails A A', a continuous line of rail for a carriage-wheel to run on, such line of rail being parallel, or sufficiently so, with the rail A². So, when the angle-piece G is in conjunction with the rail D, they, with the rails B B', will form a continuous rail in parallelism, or sufficiently so, with the outer turn-out rail B². The two movable rails C D should be a sufficient distance apart at their nearest approach to each other to allow of the passage of the wheel-flanges between them when the angle-piece is in conjunction with either of them.

In whatever direction a carriage may be passing the rail-crossing, its wheels, by their action against either the angle-piece or one of the movable rails C D, will move the said angle-piece and auxiliary rails simultaneously into the proper positions for the carriage to continue its course over and by the crossing, provided the angle-piece may not be in conjunction with the rail, C or D, over which the wheels of the carriage are to pass.

With my invention the angle-piece, instead of being brought to a very acute angle at its vertex, may there be as wide as either of the rails, and as there will be no open space of any consequence between it and the auxiliary rail,

C or D, with which it may be in conjunction, the wheel of the carriage will roll on or off it with as little detriment to it as would result to the end of a rail while the wheel might be in the act of passing over the joint of two adjacent rails.

I claim—

The combination, as well as the arrangement, of the movable angle-piece G and aux-

iliary rails C D and their stopping devices, applied together, substantially as described, with the crossing rails of the main and turnout tracks, as specified.

ADDISON ROBBINS.
